VACUUM CASTING APPARATUS

John N. Hornak, Homestead Park, and William M. Thatcher, Pittsburgh, Pa., assignors to United States Steel Corporation, a corporation of New Jersey

Application August 30, 1957, Serial No. 681,406

2 Claims. (Cl. 22—73)

This invention relates to improvements in vacuum casting apparatus and more particularly to an improved evacuable tank or chamber adapted to the casting of large ingots.

Casting in vacuum is one means of freeing metal of unwanted gases dissolved therein during melting and refining. Adoption of this practice in the casting of steel ingots intended for large forgings and the like is particularly desirable but has proven particularly difficult because of the size of castings involved. Ingots of 100 inches or more in diameter and weighing between 150 and 200 tons are commonly required. To accommodate the necessary mold and mold-stool, etc., for such ingots requires a tank or chamber 15 to 20 feet in diameter and 30 feet or more in height which, for best results, must be evacuable to an absolute pressure of less than 100 microns of mercury. Practical considerations dictate that the molten metal be teemed from a ladle outside this chamber and supported atop thereof, thus the tank or chamber must be capable of bearing the weight of the ladle and metal of the cast in addition to withstanding the pressures incident to its evacuation. This has led to the use of extremely heavy-walled chambers accessible only through the top. The use of such chambers is complicated by the fact that the ingots must be left to cool undisturbed for as long as two or three days. During this period the midportion of ingot mold reaches temperatures as high as 1000° F., and adjacent portions of the chamber are subjected to such varying degrees of heat as to expand unequally and warp. Warping can be prevented by insulating the chamber with refractory materials. However, such refractory linings absorb air and other gases when the chamber is opened; and these occluded gases are given off very slowly during evacuation making it impossible to achieve a vacuum better than 5 mm. of mercury unless uneconomically long times of evacuation are used.

It is accordingly an object of the present invention to provide a large vacuum casting chamber which can be quickly evacuated to very low pressures.

It is a further object of this invention to provide large vacuum casting chambers which can be removed from the cast ingot to permit quick cooling thereof.

It is a further object to provide a casting tank which is relatively light but at the same time is not subject to damaging stresses because of uneven expansion and contraction.

It is another object of this invention to provide a vacuum casting tank which is simple in design and efficient in use.

The foregoing and further objects will be apparent from the following specification when read in conjunction with the attached drawing wherein:

Figure 1 is a vertical section through the base and bell portions which form the casting chamber of our invention;

Figure 2 is a top view of the chamber with the ladle

2

removed, the left half of the figure showing the base with the bell portion removed; and

Figure 3 is an enlarged detail showing the seal between the base and bell portions.

Referring more particularly to the drawings, the numeral 2 designates generally the vacuum casting chamber of our invention carrying a suitable ladle L equipped with a conventional stopper and enclosing a suitable mold M. The chamber 2 comprises a bell portion 6 and a base 8, the latter disposed on a suitable foundation 10. The base 8 includes a bottom plate 12 and an upstanding rim portion 14 which terminates in a ring member 16 having an upwardly facing bearing surface 18. The rim may be stiffened by a plurality of stub columns 20 and brace plates 22 disposed at intervals about the rim below the ring member thereof and resting upon an extension of the base plate. A pipe 24 through the side of rim 14 connects the interior of the chamber to a suitable vacuum pump, not shown. A suitable mold stool S may be disposed on a supporting spiderwork of I-beams 26 inside the rim and carried by the base plate 12. Plates 28 having an inwardly sloping guide surface 27 are disposed at intervals about the ring member of the rim to guide the bell portion 6 into proper engagement with bearing surface 18. The bearing surface 18 is provided with annular groove 30 adjacent the inner edge thereof which is adapted to receive a compressible sealing ring 32 formed of resilient material such as natural rubber, neoprene rubber, silicone rubber or the like. In order to insure an effective seal, this sealing ring should be of sufficient thickness in relation to the depth of groove 30 to be compressed at least about 20% but not more than, about 30%, and, to insure a satisfactory service life, the groove and ring should be of such volume that the ring 32 may expand laterally when compressed and not overfill the groove. The bottom plate 12, rim 14 and ring 16 are joined in a gas tight manner as by continuous welds.

The bell portion 6 of the chamber comprises a ring-like bearing plate 36 to which are fixedly attached a plurality of columnar supporting members 38. Disposed on top of the supports 38 is a plurality of beams 40 carrying a plate 42 forming a platform for the ladle L which rests thereon on a suitable sealing ring 44.

Disposed within the supporting framework and attached to the bearing ring 36 is a relatively thin gauged cylindrical shell 45 closed at the top by a circular plate 46 having a dished portion 48 adjacent its juncture with the side wall of the shell. Dished portion 48 is preferably of somewhat thinner gauge than the balance of the plate 46 and by reason of its shape and flexibility provides means to compensate for unequal heating and expansion of the shell when teeming molten metal into the mold M and during such time as may elapse between teeming and the removal of the bell portion of the chamber. The cylindrical side wall of shell 45 is relieved of the dead weight of top plate 46 by suspending the latter from the plate 42 of the ladle platform by a plurality of stud bolts 50 carried by the plate 46 and extending through the plate 42. Centrally disposed of plates 42 and 46 is a tubular member 52 providing a pouring conduit through which molten metal can be teemed from the ladle L into a mold M in the evacuated chamber. Joints between the pouring conduit and plates 42 and 46, between the plate 42 and the cylindrical side wall of shell 45 and between the shell 45 and bearing ring 36 are made gas tight as by continuous welds.

In using the apparatus the mold M is positioned on the stool S, and the bell section lowered over the base being guided into proper sealing positioned by the plates 28. The ladle L containing at least a portion of the metal to be cast is then placed on plate 42 of the ladle platform to rest on the sealing ring 44 thus completely

sealing the chamber from the atmosphere. The chamber is then evacuated through pipe 24 to about 100 microns of Hg and teeming of the ingot initiated. The vacuum is maintained until the teeming is complete, care being taken to maintain sufficient metal in the ladle to seal the system during this operation. In casting of large ingots this may necessitate adding molten metal to ladle L from a transfer ladle or the like from time to time during the casting. When the mold is filled, the vacuum pumps can be shut down and the chamber restored to atmospheric pressure by bleeding-in air through a valve in exhaust line 24. The ladle and bell portion section can then be immediately removed to leave the ingot to cool undisturbed on the base.

Since the structural features of the present apparatus permit opening of the chamber immediately upon completion of casting, the present invention affords more rapid cooling than heretofore available and the bell section can be used to serve several bases. Further since the structure is such that warping is avoided without the use of insulating linings, lower vacuums can be rapidly achieved and maintained.

The foregoing example illustrates top pouring, the apparatus is of course equally adapted to bottom pouring.

While we have shown and described certain specific embodiments of our invention, we do not wish to be limited exactly thereto except as defined in the following claims.

We claim:

1. Vacuum casting apparatus comprising, a gas tight base member including an upwardly facing bearing surface having a groove therein adapted to receive a compressible sealing ring, a ring of compressible sealing material disposed in said groove, and a bell member supported by said base member, said bell member having a ring-like bearing plate adapted to rest on the rim of said base and compress said sealing ring, a plurality of spaced columnar supports attached to and rising from said bearing plate, a platform carried by said columnar supports and adapted to support a pouring ladle, a gas tight shell comprising a wall portion disposed inside said columnar supports carried by said bearing plate and attached to the latter in a gas tight manner and a top plate suspended from said platform, said top plate including a relatively thinner dished section adapted to flex under expansion 30

45

and contraction forces, a tubular member carried by said platform centrally thereof extending through and attached to said top plate, and means for evacuating the gas tight chamber formed by said bell member and base.

5 2. Vacuum casting apparatus comprising, a gas tight base member including a plate and an upwardly extending rim, said rim having an upwardly facing bearing surface having an annular groove therein adapted to receive a compressible sealing ring, a ring of compressible sealing material disposed in said groove having a thickness in the uncompressed condition about 25% greater than depth of the groove and a volume not greater than the volume of the groove, and a bell member supported by said base member, said bell member having a ring-like bearing plate adapted to rest on the rim of said base and compress said sealing ring, a plurality of spaced columnar supports attached to and rising from said bearing plate, a platform carried by said columnar supports and adapted to support a pouring ladle, a gas tight shell 10 comprising a cylindrical wall portion disposed inside said columnar supports carried by said bearing plate and attached to the latter in a gas tight manner and a circular top plate suspended from said platform, said top plate including a relatively thinner dished section adapted to flex under expansion and contraction forces, a tubular member carried by said platform centrally thereof extending through and attached to said top plate, and means for evacuating the chamber formed by said bell member and base.
